Atts.

UNITED STATES PATENT OFFICE.

LARS ANDREW LARSEN, OF BOSTON, MASSACHUSETTS, ASSIGNOR TO CARE FASTENER COMPANY, OF CAMBRIDGE, MASSACHUSETTS, A CORPORATION OF MAINE.

SEPARABLE FASTENER.

1,387,106.

Specification of Letters Patent.

Patented Aug. 9, 1921.

Application filed January 16, 1920. Serial No. 351,772.

To all whom it may concern:

Be it known that I, LARS ANDREW LARSEN, a subject of the King of Norway, and a resident of Mattapan district, city of Boston, in the county of Suffolk and State of Massachusetts, have invented an Improvement in Separable Fasteners, of which the following description, in connection with the accompanying drawings, is a specification, like characters on the drawings representing like parts.

This invention pertains to improvements in separable fasteners, and more particularly, though not exclusively, to improvements in that class of separable fasteners wherein the stud and socket are separable by relative tipping movement in one direction only.

The present invention resembles somewhat that disclosed in my copending application, Serial No. 351,771, filed herewith.

In the drawings, which show an illustrative form of one preferred embodiment of my invention:

25 Figure 1 is a front elevation of a fastener secured to a portion of a curtain or other flexible fabric;

Fig. 2 is a section on the line 2—2 of Fig. 1;

30 Fig. 3 is a rear elevation of the socket; and

Fig. 4 is an end elevation of a preferred form of stud shown in the other figures.

Referring to the drawings and to the preferred form of my invention selected for illustrative purposes, I have shown a resilient stud including a head 5, a neck 6, and a shank portion 7, the stud being split longitudinally to provide resiliency, the slots 40 preferably being continued into the base, as best shown in Fig. 4. This stud is substantially identical with the one shown in my co-pending application above referred to.

45 Coöperating with this stud, I provide a socket which preferably includes a neck-engaging plate 8 having an aperture therein through which the head of the stud can pass when compressed, the aperture preferably being proportioned to the diameter of the neck of the stud so that, when the stud is entered through the aperture, the stud resiliently engages the bottom of the neck. The stud-engaging plate is prefer-

ably, as shown, mounted on the front face 55 of the fabric, this being that side of the fabric away from the base of the stud. On the opposite side of the fabric 9, I preferably provide a strain-receiving and limiting plate 10, which may include an extended bearing support 11, preferably as shown, a lip turned rearwardly and adapted to receive, together with the bottom face of the aperture in the plate 8, the strains which normally occur on the fabric. 65

The plate 10 preferably, as shown, limits relative tipping movement of stud and socket in three directions, while permitting such relative tipping movement in the fourth direction, such permitted tipping movement being that produced by an outward strain on the bottom of the curtain in the direction indicated by the arrow in Fig. 2.

70 The socket may conveniently be attached to the fabric by prongs 12, which may project rearwardly from the plate 8, passing through the fabric and through holes in the plate 10, being clenched over the back of said plate.

75 While I have shown and described a preferred form of one embodiment of my invention, it will be understood that changes involving omission, substitution, alteration and reversal of parts, and even changes in the mode of operation, may be made without departing from the scope of my invention, which is best defined in the following claims.

Claims:

90 1. A separable fastener comprising, in combination, a stud having a head and a neck, and a springless socket, said socket providing on one side of the fabric means for engaging the neck of said stud, and on the other side of the fabric means for limiting the direction of possible relative tipping movement of said stud and socket.

95 2. A separable fastener comprising, in combination, a stud having a head and a neck, a socket adapted to be carried by the fabric and providing on one side of the fabric a plate having an aperture the periphery of which fits the neck in the stud, and strain-receiving means on the opposite side of the fabric providing a bearing surface against one side of the stud.

100 3. A separable fastener comprising, in

combination, a stud having a head and a neck, a socket adapted to be carried by the fabric and providing on one side of the fabric a plate having an aperture the periphery of which fits the neck in the stud, strain-receiving means on the opposite side of the fabric providing a bearing surface against one side of the stud, and prongs

projecting rearwardly from said plate, passing through the fabric, and clenched over the part carrying said strain-receiving means.

In testimony whereof I have signed my name to this specification.

LARS ANDREW LARSEN.
